UNITED STATES PATENT OFFICE.

WALTER SCHMIDT, OF HACKENSACK, NEW JERSEY, ASSIGNEE, BY MESNE ASSIGNMENTS, TO INTERNATIONAL MUSICAL CORPORATION, OF HOBOKEN, NEW JERSEY, A CORPORATION OF NEW JERSEY.

STRINGED MUSICAL INSTRUMENT.

Application filed April 14, 1925. Serial No. 22,940.

My invention relates to stringed musical instruments and has for its object to improve instruments of this class by providing the same with a permanent casing which will 5 serve as both a resonator and carrier for the instrument.

In carrying the invention into effect, I combine a stringed musical instrument with an open-topped case by permanently mounting 10 the sounding-board of the instrument within the case in spaced relation to the back thereof whereby the case will act as a resonator for the instrument; and I further provide the case with a removable cover for the open top 15 thereof whereby it may also serve as an enclosing carrier for the instrument.

Referring now to the accompanying drawings—

Fig. 1 is a top plan of an instrument provided with a casing in accordance with my invention, the cover of the casing being open to permit of the playing of the instrument.

Fig. 2 is a cross-section through line 2—2 of Fig. 1.

Fig. 3 is a central longitudinal section of the same, and

Fig. 4 is a perspective view of the instrument with the case closed and in condition to serve as a carrier for the instrument.

My invention broadly considered contemplates the combination of any kind of a stringed musical instrument with a casing that will serve as both a resonator and carrier for the instrument proper.

In the present instance I have shown a stringed instrument of a kind known as a "violin-zither", in which the so-called melody strings, indicated at 2, are arranged in a plane above the base or accompaniment strings, indicated at 3. Whereby they may be played with a bow by one hand as in a violin, while the lower or accompaniment strings are picked or played by the fingers of the other hand. Such an arrangement of the strings 45 however, adapting the instrument for playing as a combination violin-zither does not constitute a part of the present invention but does form the subject-matter of another application.

The sounding-board upon which the strings are mounted comprises a top board 4 secured on a frame formed of cross strips 5 and side strips 6. In the usual form of stringed instruments, the sounding-board includes a

back board corresponding in shape to the top board and secured to the back of the frame in spaced relation to the top board, the latter being formed with the usual openings, such as 7, for increasing the qualities of the sounding-board as such. 55

In accordance with the present invention, the usual back of the sounding-board is preferably omitted and the frame which carries the top 4 is mounted within an open topped case 8 with the top 4 in spaced relation to the back or bottom of the case, as shown in Figs. 2 and 3, whereby said case will serve 60 as a resonator for the instrument.

The sounding-board may be secured within the case 8 in any suitable way. In the present 70 instance its frame rests on blocks 9, 9 in the opposite ends of the case to which it is secured by suitable fastening means, such as the screws 10.

For the proper playing of the bass or accompaniment strings, these may be located in a plane at or about the top of the case 8, but in order that the melody strings may be properly played with a bow, as indicated by dotted lines in Fig. 1, these must be located or 80 positioned in a plane above the top of the case proper, as they are shown to be in Figs. 2 and 3.

When the instrument is not in use, it is adapted to be enclosed. This is accomplished 85 by providing the case 8 with a cover 12 which is hinged at one side to the case, as at 14, 14, and at its opposite side detachably connected to the case by fastening clips of any suitable or standard construction, such as indicated 90 at 15, 15.

An instrument constructed in the manner shown and described, that is, a unitary structure comprising the musical instrument proper and a resonator and carrier therefor, 95 is desirable because of increased volume in tone resulting from the employment of the resonator, greater convenience in handling and carrying resulting from the use of the enclosing case, and greater economy in construction; the latter feature resulting from the omission of the regular back-board of the instrument permitted by the employment of the case 8. 100

The two sets of strings 2 and 3 may be 105 mounted on the board 4 in the relation described by any suitable means. As shown, the bass or accompaniment strings 3 are con-

5 nected at one end to hitch pins 15 and at their opposite ends to tuning pins 16, between which they are drawn over bridges 17 and 18. The upper or melody strings 2 are ar-
10 ranged in two sets, one set—here shown as eight in number—being connected at one end to hitch or anchor pins 20 let into one side of the instrument frame, from which they pass upward through openings in a series of 15 positioning studs 21 arranged in a line parallel with one side of the instrument, and from thence over a bridge 22 to a set of tuning pins 23 mounted on the instrument adjacent one end thereof. The second set of mel-
20 ody strings—also shown as eight in number—is similarly mounted at the opposite side of the instrument. With this arrangement, the melody strings, representing sixteen notes, are positioned for convenient en-
25 gagement by the bow at opposite sides of the instrument; each string being tuned to produce its proper note in the scale when engaged by the bow at the point, indicated at α , where it is exposed at the side of the instrument between its positioning stud and the succeeding one.

What I claim is:

1. In a musical instrument, a stringed sounding board, a case with an open top, said

sounding board being mounted within said case and spaced from the bottom of the case, the case serving as back board, resonator, and carrier for the sounding board, and a cover for said case.

2. In a musical instrument, a stringed 35 sounding board, a case with an open top, said sounding board being mounted within said case and spaced from the bottom of the case, with at least some of its strings in a plane above the top of the case, the case serving as 40 back board, resonator, and carrier for the sounding board, and a cover for said case.

3. In a musical instrument, a case with an open top, a stringed sounding board therein, spacing blocks positioning said sounding 45 board above the bottom of the case, the case serving as back board, resonator, and carrier for the sounding board.

4. In a musical instrument, a case with an open top, a stringed sounding board therein, 50 spacing blocks positioning said sounding board above the bottom of the case, said sounding board having at least some of its strings above the top of the case, the case serving as back board, resonator, and carrier 55 for the sounding board.

In testimony whereof I affix my signature.

WALTER SCHMIDT.
